UNITED STATES PATENT OFFICE

WILLIAM A. SMITH, OF PHILLIPSBURG, NEW JERSEY, ASSIGNOR TO INGERSOLL-RAND COMPANY, OF JERSEY CITY, NEW JERSEY, A CORPORATION OF NEW JERSEY

PROTECTIVE DEVICE

Application filed May 5, 1928. Serial No. 275,343.

This invention relates to rock drills of the hammer type, but more particularly to a protective device adapted to be inserted in the forward closure of the cylinder, as for instance the lubricator, to act as a guiding surface for the piston extension.

One object of the invention is to protect the lubricator or its equivalent against wear caused by the action of the piston extension.

Other objects will be in part obvious and in part pointed out hereinafter.

In the drawings accompanying the specification and in which similar reference characters refer to similar parts,

Figure 1 is a longitudinal elevation partly in section of a rock drill illustrating a practical application of the invention, and

Figure 2 is a transverse view taken through Figure 1 on the line 2-2 looking in the direction indicated by the arrows.

Referring to the drawings, A represents the cylinder of a rock drill and B a back head which may be secured to the cylinder by means of side bolts C.

The cylinder A has a free exhaust port D which is controlled by a piston E reciprocable in the cylinder. The piston E may be of a well known type having a head F and a reduced extension G which extends into a chuck H for delivering blows of impact to a working implement J, only the shank K of which is indicated in the drawings.

A closure is provided for the front end of the cylinder in the form of a lubricator L comprising a body portion O having a bore P through which extends the extension G.

The front end of the body portion O carries a sleeve Q, the interior of which forms a bearing surface for the chuck H, and a flange R at the forward end of the sleeve Q lies between the front end of the cylinder A and the rearward end of a front head S for holding the lubricator L against endwise movement in the cylinder A. In the periphery of the lubricator L is an annular chamber T for the reception of lubricant intended to lubricate the movable elements of the drill forwardly of the lubricator, such as the chuck parts.

In accordance with the present invention

the bore P in the lubricator L through which the piston extension G extends is of considerably larger diameter than the piston extension and comprises a reduced portion U and a rearward enlarged portion V. Within the reduced portion U is disposed a bushing W the bore X of which forms a guiding surface for the piston extension G. At the rearward end of the bushing W is a lateral flange Y which lies in the enlarged portion V of the bore P and is of a thickness substantially equal to the depth of the enlarged portion V of the bore so that the rearward end of the flange will lie flush with or slightly below the corresponding end of the lubricator L.

In the periphery of the flange Y is a notch Z which registers with a hole b in the lubricator L. A pin c disposed in the hole b engages the notch Z for securing the bushing W firmly in the lubricator L. The hole b is preferably open at each end so that the pin c may be inserted from either end of the hole and the pin c may be of only slightly less length than that of the hole so that normally there will be only a very slight endwise movement of the pin c. Such movement of the pin however, is not objectionable since the lubricator L at all times remains stationary with respect to the cylinder, the wall of which serves to retain the pin c in the hole b.

Heretofore in drills of this type it has been the usual practice to use the bore P in the lubricator as a guiding surface for the piston extension G. After a certain period of usage the action of the piston extension G caused such wear in the body portion O of the lubricator as to necessitate the replacement of the lubricator even though other portions of the lubricator, such as the sleeve Q were only slightly affected by wear and capable of rendering service for a considerably longer period of time. Due to the present invention the lubricator is thoroughly protected against the wearing action of the piston extension and any wear caused thereby is confined to the bushing W. Therefore, whenever the bushing W becomes unfit for use the same may be readily replaced in practically the same pe-

riod of time that would be required to replace the lubricator and at a very much smaller expense.

I claim:

- 5 In a rock drill, the combination of a cylinder and a piston, an extension on the piston, a lubricator forming a closure for the front end of the cylinder, said lubricator having a bore comprising a reduced portion and an enlarged portion, a bushing in the reduced portion forming a guide for the extension, a flange on the bushing lying in the enlarged portion of the bore, said flange having a notch in its periphery, a hole in the lubricator 10 registering with said notch, and a pin in the hole engaging said notch for locking the bushing in the lubricator, said pin being retained in the hole by the cylinder.

In testimony whereof I have signed this
20 specification.

WILLIAM A. SMITH.
